(57) **CLAIM**

The ornamental design for a portable shoulder tote bag, as shown and described.

DESCRIPTION

FIG. 1 is a top, front and right side perspective view of a portable shoulder tote bag showing my new design; FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 1.

The dotted lines shown on the portable shoulder tote bag depict stitching that form no part of the claimed design. The dash-dot-dash broken lines define the boundary of enlarged views and form no part of the claimed design.

1 Claim, 10 Drawing Sheets
